United States Patent Office

Des. 179,212
Patented Nov. 13, 1956

179,212

MENORAH

Sara Rae Naimon, Milwaukee, Wis.

Application March 12, 1956, Serial No. 40,567

Term of patent 14 years

(Cl. D29—1)

Fig. 1.

Fig. 2.

Fig. 3.

Fig. 4.

The dominant features of the design reside in the portion shown in full lines in the drawing.

I claim:

The ornamental design for a Menorah, as shown and described.
